US0D1066572S

(12) United States Design Patent (10) Patent No.: US D1,066,572 S
(45) Date of Patent: * Mar. 11, 2025

(54) HANDSHOWER

- (71) Applicant: Kohler Co., Kohler, WI (US)
(72) Inventors: Margaret C. Mazz, Atlanta, GA (US);
Yutong Wu, Sheboygan, WI (US)
(73) Assignee: KOHLER CO., Kohler, WI (US)
() Term: 15 Years
(21) Appl. No.: 29/910,605
(22) Filed: Aug. 22, 2023

Related U.S. Application Data

- (60) Continuation of application No. 29/840,639, filed on May 31, 2022, now Pat. No. Des. 1,000,370, which is a division of application No. 29/753,876, filed on Oct. 2, 2020, now Pat. No. Des. 957,570.
